US00D488187S

(12) United States Design Patent (10) Patent No.: US D488,187 S
Bertram (45) Date of Patent:  Apr. 6, 2004

(54) TYPE FONT

(75) Inventor: Axel Bertram, Berlin (DE)
(73) Assignee: Heidelberger Druckmaschinen AG,
Heidelberg (DE)
() Term: 14 Years
(21) Appl. No.: 29/150,505
(22) Filed: Nov. 14, 2001

(30) Foreign Application Priority Data

May 26, 2001 (DE) 401 50 013
(51) LOC (7) Cl. 18-03
(52) U.S. Cl. D18/24
(58) Field of Search D18/24-33; 101/398,
101/399
